UNITED STATES PATENT OFFICE.

CHARLES C. LININDOLL AND LOTTIE C. LININDOLL, OF FORT EDWARD, NEW YORK.

DRESS-SHIELD FASTENER.

SPECIFICATION forming part of Letters Patent No. 763,990, dated July 5, 1904.

Application filed December 21, 1903. Serial No. 186,063. (No model.)

To all whom it may concern:

Be it known that we, CHARLES C. LININDOLL and LOTTIE C. LININDOLL, of Fort Edward, Washington county, New York, have 5 invented certain new and useful Improvements in Dress-Shield Fasteners, of which the following is a full, clear, and exact description.

Our invention relates to improvements in dress-shield fasteners, though the invention 10 can be used with almost equal facility and advantage for other purposes. It is especially intended for use or in connection with dress-shields; and the object of our invention is to produce a very cheap and simple device which 15 can be easily applied to a dress-shield, which when applied cannot be accidentally displaced, and which can also be quickly and securely attached to the waist or other garment so as to hold the dress-shield securely in place and 20 also in a manner to prevent it from wrinkling.

As above remarked, the invention can also be applied and used for other purposes.

With these ends in view our invention consists of a dress-shield fastener the construction 25 and arrangement of which will be hereinafter described.

Reference is to be had to the accompanying drawings, forming part of this specification, in which similar figures of reference refer to 30 similar parts throughout both views.

Figure 1 is a perspective view of the fastening device embodying our invention, showing it with both ends open ready for adjustment; and Fig. 2 is a longitudinal section of the 35 device, showing it closed and with both ends fastened to a dress-shield and garment.

One end of the fastener consists of a pair of jaws 10, which for cheapness and convenience are made in a single piece doubled in 40 the center, as shown at 11, and constituting at this point a part of a hinge-knuckle and the free ends being bent outward, as shown at 12, so as to enable the jaws to have their meeting edges approach one another in such a way as 45 to secure a good grip on the garment to which they are attached. This construction also prevents the fastening-sleeve 13 from slipping off the jaws, and the little bends 12^a in the jaws serve to prevent the sleeve from sliding

back and loosening the jaws once they are 50 fastened. The sleeve is endless and slides freely on the two jaws. The jaws 10 are at their middle bend recessed or cut away, as shown at 14, to provide for the hinge-knuckle 16, which is pivoted on a portion of the loop 55 15, and the latter is pivotally supported in the knuckles or bends of the jaws 10. The loop 15 also serves as a jaw, and it is preferably, though not necessarily, of a generally rectangular shape, and it comes opposite the swing- 60 ing jaw or plate 17, which is also preferably struck up from a single piece having one extension formed into the knuckle 16, already referred to, and having at its free edge a fastening projection 18, which is pointed and 65 which is of malleable material, so that it may be bent easily and doubled over the free edge of the loop or jaw 15.

In practice the fasteners are preferably applied at the lower edges and opposite parts of 70 a dress-shield, the upper edges, comprising the plate 17 and loop 15, being attached to the shield, and the lower jaws 10 are secured to a garment, such as the waist, at a point below the shield. The jaws may be placed over a 75 wrinkle, seam, fold, or other part of the garment, and the sleeve 13 is pushed down, so as to secure them.

In attaching the fastener to a shield or other article a hole is made through the article. The projection 18 is thrust through the 80 hole. The parts 15 and 17 are closed together, and then the projection 18 is doubled over a part of the loop 15, as shown clearly in Fig. 2.

From the above description it will be seen 85 that the invention is a very simple one and it is easily applied, and that when once in position both its fastening ends are made exceptionally secure.

Having thus described our invention, what 90 we claim as new, and desire to secure by Letters Patent, is—

1. A fastening device of the kind described, comprising two pairs of jaws connected at 95 their bases so as to extend in opposite directions, and means for independently fastening both pairs of jaws in closed position.

2. A fastening device of the kind described, comprising a pair of jaws having a sliding sleeve thereon to lock them, and a second pair of jaws, pivotally connected to the first pair, 5 one of the second pair having a loop member and the other having a projection constructed to be doubled over a part of the loop member.
3. A fastening device of the kind described, comprising a pair of jaws formed of a single 10 piece bent in the center to make a hinge-knuckle, the said jaws having outward and inward bends near their free ends, a locking-

sleeve sliding on the jaws, and a second pair of jaws hinged to the first and comprising a loop and a plate having a malleable projection 15 adapted to be doubled over a part of the loop.

In testimony whereof we have signed our names to this specification in the presence of two subscribing witnesses.

CHARLES C. LININDOLL.
LOTTIE C. LININDOLL.
